UNITED STATES PATENT OFFICE.

ALFRED W. FRENCH, OF PIQUA, OHIO.

EXPRESSING APPARATUS.

Application filed September 12, 1921. Serial No. 500,243.

This invention relates to expressing presses, such for example as presses of the cage type in which material is subjected to pressure to express the oil or liquid therefrom in an open-ended, upright cage into which the material is usually introduced in successive or superposed layers or charges separated by press plates and press cloths. The side walls of the usual cages are provided with small openings of some sort for the escape of the expressed liquid, such openings consisting of small drill holes or narrow slits in the lining plates in the cage, or being formed by separate, parallel bars arranged to leave narrow spaces between them. As heretofore operated, so far as I am aware, the edges of the charges of material contact directly with the inner faces of the walls of the cage in which the drainage openings are formed, and when the material is subjected to pressure, solid particles of the meal or material squeeze out and clog the drainage openings more or less so that the oil or liquid has difficulty in escaping, and, therefore, a much longer time is required for the expressing operation than if a freer escape of oil were possible. This is particularly the case when operating upon some materials, such for instance as copra, in which the flow of oil is copious and has a tendency to wash away some of the meal with it. For the sake of brevity of description, the material is hereinafter called "meal" and liquid "oil".

The primary object of the invention is to provide cage presses with means which will insure a ready escape for the expressed oil and prevent the clogging of the small drainage openings of the cage. Other objects of the invention are to accomplish this result by the provision of a cloth, mat or analogous, porous, drainage medium between the meal being pressed and the drainage openings in the wall of the cage, which mat or drainage medium is adapted to permit free passage of the expressed oil through the same, but confine the meal and prevent the same from entering and clogging the drainage openings in the wall of the cage; also to construct the press cage so as to facilitate the charging and discharging thereof and reduce to the minimum the wear on the mat or porous drainage medium, due to pressure and friction of the mat against the cage wall when compressing the meal in the cage and when discharging the

pressed cakes from the cage; also to prevent the meal from packing more densely in one side of the cage than in the other portions thereof; and also to improve cage presses in the other respects hereinafter described and set forth in the claims.

In the accompanying drawings:

Fig. 1 is a vertical section of a cage press embodying the invention.

Fig. 2 is a plan view on an enlarged scale of the press cage, a part being broken away.

Fig. 3 is a fragmentary horizontal section thereof on line 3—3, Fig. 4.

Fig. 4 is a vertical section of the press cage.

Fig. 5 is a similar view of the upper portion of the cage showing the drainage mat folded over on the top cake.

Fig. 6 is a fragmentary section showing the position of the parts when the charging box advances over the cage to deposit its charge in the cage.

Figs. 7 and 8 are fragmentary elevations showing the raised and lowered positions respectively of the hinged plate at the rear side of the cage.

A represents the cage of a cage press. The cage, except as hereinafter explained, may be of any suitable construction, the cage shown in the drawings consisting of the usual hollow, open-ended, steel shell or casting provided interiorly with vertical spaced ribs *a* and suitable drainage or lining plates or members *B* secured against the inner edges of the ribs which brace the lining plates. These lining plates are provided with narrow slits *b* or other suitable openings through which the expressed oil escapes into vertical flow channels *a'* formed between the ribs *a* in the walls of the cage. In the cage shown, the slotted drainage plates are provided at the four upright sides of the cage, but it is sufficient for the purposes of this invention to have drainage openings at only one side of the cage, and the remaining walls of the cage can be made solid or without drainage openings if desired.

C represents the usual meal or charge box movable horizontally over the top of the cage for depositing the charges of meal in the cage, and *d* *d'* represent respectively press plates and press cloths of any usual or suitable kind, which are used to separate the charges of meal in the cage to facilitate the escape of oil to the sides of the cage.

E represents a porous or pervious drain-

age medium adapted to be introduced into the press cage between the charges of meal and the inner face of a side wall of the cage having the drainage openings. This drainage medium preferably consists of a cloth, mat or analogous fabric, of suitable fibrous material which forms a screen between the material and the wall of the cage through which the expressed oil can readily flow to the drainage openings in the cage wall, but which is adapted to confine the meal or fine, solid particles and prevent the escape of the same into the drainage openings. Cocoa matting made from the coir fibre of the coconut has been found to be eminently satisfactory for the purpose, since it holds back the meal while permitting a very free flow of the oil, and will not close up the small drainage slits or openings in the cage wall when pressed against the same. This material is also comparatively inexpensive, strong and durable. The mat may consist of a plurality of short lengths of material either separate or attached together, or of two or more thicknesses of like or different material, as may be most suitable for the particular material being pressed.

Preferably, the mat E is loose or disconnected from the press cage and is placed in the same by feeding the mat down into the cage as the cage is being filled and as the ram F descends to make room for the successive charges of meal. For instance, the lower end of the mat can be inserted and held between the ram and a bottom plate f which is placed in the cage on the ram, or detachably connected with the ram in any other suitable way so that as the ram descends, the mat E, which may hang over the upper edge of the cage, will be drawn down into the cage. When the cage has been filled, the upper end of the mat can be turned over on the top cake or charge of material as indicated at 10, or left hanging out of the cage.

When pressure is applied, the loose meal comprising the charges or cakes will be compressed in the cage to a much smaller volume and the mat E will also be compressed or collapsed endwise in the cage as the cakes are compressed. This causes a movement of the mat against the side wall of the cage, and the pressure causes the meal to spread and exert a lateral pressure against the mat which would cause considerable friction and wear on the mat unless prevented. Under the heavy pressure to which the meal is subjected to express the liquid, the cakes expand laterally and retain a certain degree of elasticity, so that in ejecting the pressed cakes from the cage the mat would also be subjected to objectionable friction and wear if used in a cage of ordinary construction. Press cages have been made with a taper to facilitate the discharge of the pressed cakes

therefrom, but only a very slight taper has been used so as not to interfere with the settling of the charges in the cage when filling the latter.

In order to relieve lateral pressure and friction on the mat E and at the same time ensure the proper settling of the charges in the cage as the ram descends when filling the cage, the latter is constructed so that the inner face of the wall with which the mat E contacts, converges downwardly toward the opposite wall, and a cover plate 11 may be provided which projects inwardly beyond the upper edge of the inner face of the wall. When the charging box C passes over the top of the cage to deposit its charge of meal in the cage in the usual manner, the overhanging inner edge of the cover plate 11 causes a clearance in the cage between the charge of material and the drainage mat E, as indicated at 12. When, therefore, the charges are lowered in the cage by the descent of the ram to make room for succeeding charges, they will not contact with or bear strongly against the inclined face of the mat in the cage, and the inclination of the side of the cage will not interfere with the charges settling properly in the cage. This clearance or looseness in the material in the cage next to the drainage mat also assists, it is believed, in giving a freer drainage of the oil. The cover plate is adapted to be moved so as not to overhang the chamber of the cage and thus not obstruct the pressed cakes from being ejected through the upper end of the cage, and for this purpose the cover plate 11 in the construction shown is a loose plate removably retained in place on the upper end of the cage and it can be removed when the cage is to be discharged. After the material is thoroughly pressed and the ram is moved up in the cage to push out the cakes, the lateral pressure of the cakes against the drainage mat will be relieved almost immediately after the cakes are started upwardly, due to said inclination of the cage wall at this side, thereby eliminating friction and wear on the mat and reducing the pressure required to eject the cakes. This advantage is particularly emphasized in cage presses of the kind disclosed in United States Letters Patent No. 1,360,205, granted to me November 23, 1920, in which the cage A is charged in a filling press having a sub-cage or cage extension, shown at 14 in the drawings, below the cage A and adapted when filling the cage, to receive a number of charges, which are afterward pushed up into the main cage A and compacted with the other charges in the latter in order to get a larger number of charges in the main cage, which is then removed from the filling press and placed in another press in which the final high pressure is applied.

The described construction of the cage A enables the charges to be pushed from the sub-cage into the main cage in much less time, due to the fact that the oil expressed in the filling cage can escape much more freely and the speed of upward movement of the ram is determined by the rate of escape of the liquid.

15 represents a plate or member adapted to project inwardly over the cage chamber from the upper edge of the rear side of the cage A, or that side thereof from which the charging box C advances over the cage to deposit the charges in the cage. The plate 15 is preferably hinged in any suitable manner so as to swing from a vertical position shown in Fig. 7, to a horizontal inwardly projecting position, shown in Fig. 8. In the vertical position the plate does not overhang the cage chamber and will not interfere with the introduction of the press plates and cloths d d' into the cage, nor obstruct the discharge of the pressed cakes from the cage. A spring 16 connected to a crank arm 17 on one end of the plate 15, or other suitable actuating means, is provided for normally holding the plate 15 yieldingly in its vertical position and returning it when released to that position. When the charge box advances to deposit a charge of meal in the cage, it engages and swings the plate 15 down to its horizontal position, as shown in Fig. 6, and holds the plate in this position while the charge box is moving forwardly and backwardly above the cage. The plate 15 then overhangs somewhat the cage chamber and prevents the meal from packing as densely at this side of the cage as it otherwise would do. The charge box has a tendency on its return stroke to drag and pack the meal against the rear side of the cage so that the density of the meal is greater at the rear of the cage against the rear drainage plate B. The plate 15, however, prevents this packing and gives a little looseness of the meal at the rear of the cage. This looseness disappears when the pressure is applied, making the cake of substantially uniform density throughout, and in addition the looseness cooperates with the clearance or looseness before mentioned at the opposite side of the cage in enabling the charges to follow the ram down or settle properly in the cage.

55 As shown, each of the plates 11 and 15 is provided with a depending lip 18 at its inner edge to make the plates more efficient in giving the described clearance or looseness in the meal at the front and rear sides of the cage but these lips are not indispensable.

I claim as my invention:

1. The combination with a press cage having an open end for the introduction of the material to be pressed, a side wall provided with small openings for the escape of the ex-

pressed liquid, a plurality of charge separating members disposed in said cage substantially transversely to said side wall for maintaining the charges of material in the cage separated and for facilitating escape of the expressed liquid to the side wall, and a ram which is movable endwise in the cage for applying pressure to the material through said charge separating members, of a loose, movable porous drainage medium and means whereby said drainage medium is drawn into the cage along said side wall thereof and between the same and the edges of the separated charges of material in said cage when the ram is retracted in charging the material into the cage.

2. The combination with a press cage having an open end for the introduction of the material to be pressed, a side wall provided with small openings for the escape of the expressed liquid, a plurality of charge separating members disposed substantially transversely to said side wall for maintaining the charges of material in the cage separated and for facilitating escape of the expressed liquid to the side wall, and a ram which is movable endwise in the cage for applying pressure to the material through said charge separating members, of a loose fibrous drainage fabric arranged to enter the open end of the cage and to be connected to a movable part in the cage so as to be drawn into the cage across the side edges of the separated charges of material in the cage and between said side edges and the side wall of the cage when the ram is retracted in charging the material into the cage.

3. The combination with a press cage having an open end for the introduction of the material to be pressed, a side wall provided with small openings for the escape of the expressed liquid, said side wall converging towards the opposite wall of the cage from the open end thereof, and a plurality of drainage members in said cage disposed substantially transversely to said side wall and separating the material in said cage into a plurality of batches, of a porous drainage medium within said cage between said converging side wall thereof and the edges of the batches of material in the cage for preventing solid particles of the material from clogging said escape openings.

4. The combination with a press cage having an open end for the introduction of the material to be pressed, a side wall provided with small openings for the escape of the expressed liquid, a plurality of drainage members disposed substantially transversely to said side wall and separating the material in said cage into a plurality of batches for effective drainage and for facilitating the escape of the expressed liquid to the side wall, of a loose fibrous drainage fabric arranged to enter the open end of the cage, and

means whereby said drainage fabric is drawn into the cage between said side wall and the edges of the separate batches of material when the material is charged into the cage, for receiving the drainage from said transversely disposed drainage members and preventing solid particles of the material from clogging the escape openings in said side wall.

10. 5. The combination with a press cage having an open end for the introduction of the material to be pressed and a side wall provided with small openings for the escape of the expressed liquid, said side wall converging toward the opposite wall of the cage from the open end thereof, of a porous drainage medium within said cage between said converging side wall thereof and the material being pressed for preventing solid particles of the material from clogging said escape openings, and a member which projects inwardly from said converging side wall at the open end of the cage for causing a looseness in the material in the cage adjacent said drainage medium.

15. 6. The combination with a press cage having an open end for the introduction of the material to be pressed and a side wall provided with small openings for the escape of the expressed liquid, said side wall converging toward the opposite wall of the cage from the open end thereof, of a member which projects inwardly from said converging side wall at the open end of the cage for causing a looseness in the material in the cage adjacent said converging side wall.

20. 7. The combination with a press cage having an open end for the introduction of the material to be pressed and a side wall provided with small openings for the escape of the expressed liquid, said side wall converging toward the opposite wall of the cage from the open end thereof, of a member which projects inwardly from said converging side wall at the open end of the cage for causing a looseness in the material in the cage adjacent said converging side wall, and means for moving said member from its inwardly projecting position so as not to obstruct the discharge of the material through said open end of the press.

25. 8. The combination with a press cage having an open end for the introduction of the material to be pressed and a side wall provided with small openings for the escape of the expressed liquid, and a charge box which moves forwardly and backwardly over said open end of the cage to deposit charges of material in the cage, of a member which projects inwardly from the rear wall of the cage at the open end thereof for causing a

looseness of the material in the cage adjacent said member.

30. 9. The combination with a press cage having an open end for the introduction of the material to be pressed and a side wall provided with small openings for the escape of the expressed liquid, and a charge box which moves forwardly and backwardly over said open end of the cage to deposit charges of material in the cage, of a member which is positioned to project inwardly from the rear wall of the cage at the open end thereof when the charge box advances for causing a looseness of the material in the cage adjacent said member and is movable out of said inwardly projecting position when the charge box has been retracted from over the cage.

35. 10. The combination with a press cage having an open end for the introduction of the material to be pressed and a side wall provided with small openings for the escape of the expressed liquid, and a charge box which moves forwardly and backwardly over said open end of the cage to deposit charges of material in the cage, of a member which is actuated by the charge box to project inwardly from the rear wall of the cage at the open end thereof when the charge box advances for causing a looseness of the material in the cage adjacent said member and moves out of said inwardly projecting position when the charge box has been retracted from over the cage.

40. 11. The combination with a press cage having an open end for the introduction of the material to be pressed and a side wall provided with small openings for the escape of the expressed liquid, and a charge box which moves forwardly and backwardly over said open end of the cage to deposit charges of material in the cage, of a spring actuated member which normally stands upright and is moved to project inwardly from the rear wall of the cage at the open end thereof when the charge box advances for causing a looseness of the material in the cage adjacent said member.

45. 12. The combination with an upright press cage adapted to receive superposed layers of material to be pressed separated by horizontally disposed press plates, and having a substantially vertical side wall provided with small openings for the escape of the expressed liquid, of a separate fibrous drainage fabric strip, and means whereby said drainage fabric is moved in and out of said cage and positioned when in said cage between said side wall and the material being pressed for preventing solid particles of the material from clogging said escape openings.

ALFRED W. FRENCH.
